UNITED STATES PATENT OFFICE.

OSCAR L. BARTLETT, OF NEW YORK, N. Y.

MACHINE FOR THE CONSTRUCTION OF HAMPERS.

Application filed January 19, 1925. Serial No. 3,524.

This invention relates to improvements in machines for the construction of hampers and has particular reference to the formation of a hamper for use in the shipment of such fruits as bananas and the like.

The principal object of the invention resides in a device which includes a means for supporting the staves in position for receiving the outer hoops, after which the inner 10 hoops are moved to their respective positions during which time the staves are expanded against the outer hoops thereby simplifying the operation of the manufacture of a hamper of this particular type.

With these and other objects in view, the invention resides in certain novel construction and combination and arrangement of parts, the essential features of which are hereinafter fully described, are particularly 20 pointed out in the appended claims, and are illustrated in the accompanying drawing, in which:—

Figure 1 is a perspective view of my invention.

Figure 2 is a vertical sectional view through the same showing the normal position of the parts in full lines, and the position of the parts in dotted lines after the same has been operated to move the inner 30 hoops to their respective positions.

Figure 3 is a horizontal sectional device on the line 3—3 of Figure 2.

Figure 4 is a view of a hamper after being removed from the machine.

Figure 5 is an enlarged detail sectional view of the mouth of the hamper showing the manner in which a cover is supported.

Referring more particularly to the drawing, the reference numeral 10 designates my 40 improved hamper machine which has been designed for constructing hampers such as shown at 11 in Figure 4 of the drawing and which includes spaced staves A arranged in frusto-conical manner to provide tapering 50 side walls, outer hoops B and inner hoops C.

The machine 10 includes a base 12 from which rises a post or rod 13, the lower end of the rod being anchored to the bottom wall of the base, while the upper end of the 55 rod supports a stationary disk 14. A similar disk 15 is supported upon the top of the base but is slightly larger than the disk 14, and which disks co-act to support the staves A in a manner to receive the hoops B and C.

Radially disposed members 16 extend beyond the periphery of the disks 14 and 15

and co-act to space the staves equi-distantly at opposite ends. The projecting portions of the members 16 are capable of being moved inwardly of the periphery of the 60 disks for facilitating the application of the outer hoops.

A tubular rod 17 encircles the rod 13 for the major portion of its length and is slideable thereover, the same having secured thereto spaced heads or disks 18. The lower end of the tubular rod rests upon one end of a lever 19 which is pivoted or fulcrumed between its ends as at 20, the other end of the lever extending exteriorly of the base 70 through a slot 21 and terminating in a foot pedal 22. The weight of the tubular member and the disks 18 is sufficient to normally hold the foot pedal 22 in a raised position where pressure can be applied by the foot 75 of the operator when it is desired to move the disks or heads 18 upward with respect to the shaft 13 and disks 14 and 15 in order to expand the staves A against the outer hoops B.

The rod 13 is formed with sets of radially disposed arms 23 which extend between certain staves for supporting the intermediate outer hoops B prior to the expanding of the staves in a manner to be more fully explained. The arms 23 extend through vertical slots 24 formed in the tubular rod 17 to permit the said rod to move with respect to the rod 13.

In operation, the heads 18 are disposed in their normal position shown in Figure 2 in full lines and a hoop C placed upon each. The staves A are placed against the stationary disks 14 and 15 in a circular manner and are held in spaced relation by means of the members 16. The outer hoops C are dropped over the staves, until the same rest upon arms 23 and members 16. When the parts of the hamper have been thus assembled, a plate 25 is placed over the top of the staves and pressure applied thereto by the hand of the operator, while a foot of the operator is simultaneously placed upon the foot pedal 22 and depressed. The inner end of the lever 19 will now cause the tubular rod 17 carrying the heads 18 to move upward and by reason of the staves being arranged in a frusto-conical arrangement and the heads moving toward the narrow end of the staves, the heads will force the inner hoop C against the inner faces of the staves, the said staves in turn being expanded

against the outer hoops B. When the disks 18 have reached the limit of their upward movement, pressure is released from the foot pedal whereupon the tubular member 17 5 will gravitate to its normal position leaving the inner hoops in their respective positions. The hamper may now be removed from the machine and the bottom and top inner hoops applied in the usual manner. From the 10 foregoing description, it will be seen that during the expanding operation, the friction between the staves and the outer hoops is greater than the friction between the inner hoops and the staves thereby producing a 15 strong and rigid structure.

In Figure 5 of the drawing, I have illustrated the manner of securing a cover 26 between the end outer hoop B and the top ends of the staves A. The cover is formed of 20 any suitable flexible material such as paper or cloth, the same being closed by a draw string 27. By passing the ends of the material over the outer hoop and upward between the outer hoop and the staves, water 25 will drain off the cover without passing between the hoops and into the interior of the hamper which would occur should the cover be fastened in any other manner. In other words, the arrangement of securing the cover to the hamper seals the top of the hamper 30 against leakage.

After all the hoops and the bottom have been applied in the usual manner, the whole structure is placed in a nailing machine for 35 securely holding the parts in their proper positions.

What is claimed as new is:—

1. In a machine of the class described, the combination of means for holding a plurality of staves in converging relation to each other, outer hoops, means for supporting said outer hoops about said staves, inner hoops, and means for moving said inner hoops longitudinally into wedging contact with the inner faces of the staves to expand said staves against said outer hoops.
2. In a machine of the class described, the combination of means for holding a plurality of staves in spaced annular formation and in converging relation with respect to each other, outer hoops, means for supporting said outer hoops about said staves, inner hoops, and manually operable means for moving said inner hoops longitudinally into 55 wedging contact with the inner face of the staves to expand said staves against said outer hoops.
3. In a machine of the class described, the combination of means for holding a plurality of staves in a frusto-conical arrangement, outer and inner hoops, means for sup-

porting said outer hoops about said staves, heads for receiving said inner hoops, and actuating means for moving said heads longitudinally with respect to said staves to cause said inner hoops to frictionally engage the inner faces of said staves to expand the same against said outer hoops.

4. In a device of the class described, the combination of a pair of spaced disks, means for holding a plurality of staves in frusto-conical arrangement and in spaced relation about said disks, spaced outer hoops encircling said staves, inner hoops, spaced movable heads for supporting said inner hoops, and means operable for moving said heads upward in a vertical direction to move said inner hoops into frictional engagement with the inner faces of the staves to cause said staves to be expanded against said outer 80 hoops.

5. A machine of the class described comprising stave supporting means, outer hoop supporting means, inner hoop supporting means, and actuating means for moving said last means longitudinally with respect to said first two mentioned means.

6. A machine of the class described comprising a base, a stationary rod rising from said base, a disk supported at the top of said rod, a stationary disk mounted upon the top of said base, spacing members extending radially from said disk, outer hoop supporting means carried by said rod, a tubular rod encircling said stationary rod and slidable thereover, spaced heads carried by said tubular rod and said disks, and means for moving said tubular member in a longitudinal direction with respect to said stationary rod to cause said heads to move longitudinally with respect to said outer hoop supporting means.

7. A machine of the class described comprising a base, a stationary rod rising from said base, a disk supported at the top of said rod, a stationary disk mounted upon the top of said base, and of a larger diameter than said first disk to cause the staves to lie in converging relation, spacing members extending radially from said disks, outer hoop supporting means carried by said rod, a tubular rod encircling said stationary rod and slidable thereover, heads carried by said tubular rod of different diameters and movable longitudinally with respect to said disks, and foot actuated means for moving said tubular member in a vertical direction with respect to said stationary rod.

In testimony whereof I have affixed my signature.

OSCAR L. BARTLETT.
